(57) **CLAIM**

The ornamental design for a capillary electrophoresis cartridge in a container, as shown and described.

DESCRIPTION

FIG. 1 is a front perspective view of a capillary electrophoresis cartridge in a container.

FIG. 2 is a front view of the capillary electrophoresis cartridge in a container shown in FIG. 1.

FIG. 3 is a back view of the capillary electrophoresis cartridge in a container shown in FIG. 1.

FIG. 4 is a side view of the capillary electrophoresis cartridge in a container shown in FIG. 1.

FIG. 5 is a side view of the capillary electrophoresis cartridge in a container shown in FIG. 1.

FIG. 6 is a top view of the capillary electrophoresis cartridge in a container shown in FIG. 1.

FIG. 7 is a bottom view of the capillary electrophoresis cartridge in a container shown in FIG. 1; and,

FIG. 8 is a front perspective view of the capillary electrophoresis cartridge shown in an alternate configuration with the lid closed.

The broken lines shown in the drawings illustrate portions of the capillary electrophoresis cartridge that form no part of the claimed design.
